United States Patent

Des. 239,098
Patented Mar. 9, 1976

239,098

SUBMARINE

Richard Thomas Robinson, 400 E. Oak,
Lompoc, Calif. 93436

Filed May 14, 1975, Ser. No. 577,275

Term of patent 14 years

Int. Cl. D12—06

U.S. Cl. D12—65

FIG. 1

FIG. 2

FIG. 3

FIG. 4

FIG. 5

FIG. 6

FIG. 1 is a perspective view of a submarine showing my new design;

FIG. 2 is a right side elevational view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a submarine, substantially as shown.
